ATTORNEY

UNITED STATES PATENT OFFICE.

JOHN PARKHILL, OF ROCHESTER, MINNESOTA.

ROOF-FRAMING SQUARE.

Application filed September 19, 1921. Serial No. 501,782.

To all whom it may concern:

Be it known that I, JOHN PARKHILL, a citizen of United States, residing at Rochester, in the county of Olmsted and State of Minnesota, have invented certain new and useful Improvements in Roof-Framing Squares, of which the following is a specification, reference being had therein to the accompanying drawing.

10 The present invention relates to a square adapted especially for use by carpenters for use in marking the rafters of a roof frame, although useful for other similar purposes, and the invention has for an object the provision of a novel device of that kind which is simple in use and efficient and accurate in the results obtained.

Another object is the provision of a square having such graduations on the arms thereof 20 and gages slidably mounted on said arms, in order that the square can be conveniently used for laying out and marking off different angles, such as when cutting rafters, and the like.

25 A further object is the provision of such graduations arranged in a novel manner on the square for obtaining the desired results quickly and accurately, and to facilitate the cutting of the rafters or other boards.

30 A still further object is the provision of novel gages mounted on the arms of the square for cooperation with the graduations and to assist in positioning the square on the rafter or board.

35 With the foregoing and other objects in view, which will be apparent as the description proceeds, the invention resides in the construction and arrangement of parts hereinafter described and claimed, it being understood that changes can be made within 40 the scope of what is claimed without departing from the spirit of the invention.

The invention is illustrated in the accompanying drawing, wherein—

45 Figure 1 is a plan view of the improved square, portions being broken away.

Figs. 2 and 3 are enlarged cross sections on the respective lines 2—2 and 3—3 of Fig. 1.

50 Fig. 4 is a sectional detail on the line 4—4 of Fig. 3.

Figs. 5, 6 and 7 are diagrams showing the derivation of scales C and D.

55 Fig. 8 is a diagram showing the derivation of scales A and B.

Any suitable square can be used to include

the present improvements, and, as shown in the drawing, the square is of the ordinary type, and includes the long arm or blade 10 and the short arm or tongue 11. The outer edges of the arms 10 and 11 are graduated from the outer angle of the elbow, as at 12 and 14, respectively, and the inner edges of the arms 10 and 11 are similarly graduated from the inner angle of the elbow, as at 13 and 15. The unit of measurement as herein described is a foot and the fractional graduations are in inches as shown, although the metric or other unit of measurement can be used. The fractional graduations have been eliminated for purpose of simplicity and the use thereof is of course well known.

In carrying out the invention, the arm or blade 10 is provided with the scales A and B thereon, while the arm or tongue 11 is provided with the scales C and D thereon.

The scale A is obtained from the derivation as depicted in the diagram designated Fig. 8. This diagram includes a straight base line HE, from which the perpendicular lines FG and I rise. Any length might be used for the distance between E and F, but in using the foot and inch as a basis of measurement, the line EF is one foot in length, while the line FG is divided off in inches from the point F upward. Thus, the graduations on the line FG represent the rise in inches of the roof or inclined surface per running foot horizontally, known in the trade as "the rise to the foot of run" or simply "the rise." Other units of measurement could, however, be used for the several scales of graduations. The distance between F and H is equal to the radius of a circle which circumscribes a square of which a perpendicular extending from the center of the square to either side, or the radius of the inscribed circle, is equivalent to the length of the line EF. Thus, referring to Fig. 5 in which a square is shown on a smaller scale than Fig. 8, the perpendicular KJ is equal to the line EF, and KL is the radius of the circumscribing circle. The line HF is equal to the radius KL. The perpendicular I is a distance from the point H equal to the distance between the points E and F, or one foot, the line HI being the same as the line EF in length. Lines are drawn from the points E and H to the inch graduations on the line FG, and the lines or distances E¹, E², etc., represent the graduations 16 of the scale A.

These graduations 16 start from the 12 inch graduation of the outer graduations 12 of the arm or blade 10, and run away from the elbow of the square. The outer edge of such arm or blade being used for the graduations of scale A. Thus, the graduations of such scale A are distances from the outer angle or corner of the elbow of the square, to the respective graduations and are equal to the 10 lines or distances E^1 , E^2 , etc., of the diagram Fig. 8. The graduations of scale A thus represent the lengths of the hypotenuses of the right triangles for the different inches in rise for a running distance horizontally of 15 one foot. The distances between the outer edge of the tongue 11 and graduations of the scale A thus represent the lengths of hypotenuses of right triangles each having as one of its sides or the base the unit or measurement (one foot) and having as their other sides or heights a series of increasing graduated measurements for increasing "rises" per unit.

Scale B is also derived from Fig. 8, it being noted, as above described, that the line HF is the radius of the circle circumscribing a square of which the line EF is the radius of the inscribed circle or a perpendicular from the center of the square to one 25 side, as represented in Fig. 5, while the perpendicular line I is a distance from the point H equal to the line FF . The points of intersection of the line I by the lines extending from the point H to the graduations on 30 the line FG constitute the graduations of the scale B, and such graduations are proportionately smaller or shorter in spacing than the graduations of the scale A, accordingly. The graduations 17 of the scale B, which are 35 also measured from the outer edge of the arm or tongue 11 of the square, the same as the scale A, represent the distances of the lines from the point H to the line I , which are correspondingly shorter than the lines E^1 , E^2 , etc., and such graduations 17 also start from the 12 inch graduation of the scale 12, such 12 inch graduation representing the line HI and also the line EF . The 40 measurements from the outer edge of the tongue 11 to the graduations of the scale B also represent the lengths of hypotenuses of right triangles each having as one of its sides or the base the unit of measurement 45 and having as their other sides or heights a series of increasing graduated measurements, but these increasing graduated measurements bear the proportions to the increasing "rises" per the unit of measurement (graduated on the line FG of Fig. 8) as the radius of an 50 inscribed circle of a square bears to the radius of the circumscribed circle of such square. In other words, the distances marked off on the line I in Fig. 8 bear 55 the proportion to the distances measured off on the line FG that the radius (EF or HI)

of an inscribed circle of a square bears to the radius (FH) of the circumscribed circle of such square.

Scales C and D are derived from a series of regular polygons having four, five, six and up to any suitable number of sides and angles. Thus, Fig. 5 represents the square, Fig. 6 the pentagon, Fig. 7 the hexagon, etc., the remaining polygons not being shown, inasmuch as the principle will be understood 70 from Figs. 5, 6 and 7. In the polygons, the perpendiculars KJ from the centers to the sides or the radii of the inscribed circles are equal, representing one foot in length, whereas the radii of the circumscribing circles are 75 of gradually decreasing lengths from the square root of 2 to 1 as represented by the lines KL . The line KL of the square is the longest in length, and the lines KL of the succeeding polygons having five, six and more sides gradually decrease in length and approach the length of the line or perpendicular KJ (12 inches). The distances KL are marked off on the arm or tongue 11 from the outer edge of the arm or blade 10, represented by the graduations 18 of scale C, and such graduations run from the end of the arm or tongue 11 toward the angle but do not reach the 12 inch graduation of the scale 14. The numbers of the graduations 90 18 correspond with the number of sides (and angles) of the polygons from which the measurements were obtained.

Scale D is also derived from such polygons and the graduations 19 thereof are 95 measured from the outer edge of the arm or blade 10 also, the same as the graduations 18. The graduations 19 are also numbered according to the number of sides (and 100 angles) of the polygons from which the measurements were obtained. Thus, the graduations of the scale D represent the half-lengths of the sides of the corresponding polygons JM of Figs. 5, 6, 7 and so on. The length of distance between J and M of Fig. 5 is one foot or twelve inches, while the lengths JM of the successive polygons gradually decrease in length and approach zero. The graduations of the scale D thus 105 run from the 12 inch graduation of the scale 14 toward the outer edge of the arm or blade 10.

Even if differently placed, such scales A, B, C and D would be useful, but the arrangement as shown is most desirable and useful. The use of such scales is facilitated by two adjustable gages as will be presently described.

A gage 20 is disposed on or across the arm or blade 10 for longitudinal sliding movement thereon, and has the portions 21 and 22 extending at obtuse angles to clear the outer and inner edges of the blade, respectively, and a flange 23 extends from the portion 21 at an angle to bear against and 125 ex-

tend across the outer edge of the blade 10. The portions 21 and 22 permit the intermediate portion of the gage 20 to bear snugly and flatly on the blade, especially 5 when the gage is tightened on such blade. The gage or slide 20 has a straight edge 24, and the corresponding end of the flange 23 has a knife edged bearing 25 which is on a line with the dependent straight edge 24 10 which registers with the graduations of the scales A and B, whereby such knife edged bearing will also register with the corresponding graduations. Said bearing is also in line with the outer edge of the blade 10. 15 In order to clamp the gage or slide 20 to the blade 10 with the flange 23 and knife edged bearing 25 thereof tightly against the outer edge of said blade, the portion 22 has a flange 26 extending in the same direction 20 as the flange 23 to project across the inner edge of the blade, and a resilient U-clamp 27 straddles the flange 26 with one portion overlapping said flange and the other portion bearing against the inner edge of the 25 blade, as seen in Fig. 2. A screw 28 is threaded through the flange 26 and corresponding portion of the clamp 27 and bears against the other portion of said clamp to spring same against the blade, thereby 30 clamping the gage or slide on the blade and pulling the flange 23 tightly against the outer edge of the blade. By loosening the screw 28, the gage can be readily slid along the blade to bring the straight edge 24 on 35 the desired graduation of either scale A or B.

The gage or slide of the tongue 11 is indicated at 29 and bears on said tongue. Said gage has a flange 30 extending at an 40 angle therefrom to project across and bear against the outer edge of said tongue. Said flange has the ears 31 bent at obtuse angles to extend under the outer edge portions of the tongue, and one corner of one ear 31 45 provides a knife edged bearing 32 on a line with the straight edge 33 of said gage, said bearing 32 also being on a line with the outer edge of the tongue 11. Both gages thus have straight edges facing the angle, 50 or elbow of the square, with knife edged bearings on a line with said straight edges and outer edges of the arms of the square, to facilitate the positioning of the square on the timber, the elbow or angle of the 55 square being placed on the timber, and the bearings 25 and 32 against the edge or side of such timber. This will position the outer edges of the arms in predetermined angles on the timber, according to the positions of 60 the gages.

In order to clamp the gage 29 in its adjusted position, a stem 34 is secured to the flange 30 and extends across the bottom side of the tongue 11 and through a U-shaped 65 clamp 35 which straddles the inner edge por-

tion of the tongue, and a nut 36 is threaded on said stem and bears against the clamp 35 for drawing the stem 34 to clamp the flange 30 against the outer edge of the tongue. 70

The straight edges of the gages are disposed nearest to the elbow or vertex of the square, and the knife edged bearings of the gages are disposed at the intersections of the outer edges of the arms and straight edges of the gages. In using the square, the elbow or angle portion thereof is placed on the timber with the knife edged bearings of both gages resting against the edge or side of the timber, and the marks are made 80 along the outer edges of the arms.

Directions to set the gages at any of the ordinary graduations of the square refer invariably to those graduations of scales 12 and 14 along the outer edges of the arms. 85

The majority of buildings are rectangular (four sided polygons) but those with six, eight, sixteen or more sides are not uncommon. Each number marked on the scales C and D gives the framing for the 90 polygon which has the corresponding number of sides. For example, the gage 29 set at 4 of either scale C or D gives the framing for a four sided structure; at 6 a six sided structure, etc. 95

This roof-framing square gives accurate, complete and quick measurements, and is extremely simple in use, there being no calculations to make, and the directions for use can be simple. In many cases, it is only 100 necessary to set one gage. Thus, to mark all common rafters, all jack rafter side bevels, all hip side bevels, and a number of other cuts (over 1200 in all) the gage 29 remains at 4 on scale D. Besides all the more 105 commonly used cuts, lengths and bevels, this square gives the more difficult—such as regular hip and valley rafters; both purline cuts at hip or valley rafter; hip lengths for any part of a foot of run; common difference in lengths of jack rafters for any distance apart; depth of backing on hips; difference between the lengths and cuts of un-backed hip and valley rafters; hood rafters; end cuts on hips to correspond with square 110 cuts on ends of projecting common rafters, etc. The square is also useful in making polygon miter cuts and hopper cuts, and much other difficult framing. 115

Form positions of gages to mark common 120 rafters, any pitch, any polygon, the directions can read "4 on D, rise on blade." The plumb cut is marked by the blade, horizontal cut by tongue, and by marking the distance between the gage bearings consecutively, once for each foot of run, gives the whole length of the rafter. Thus, by placing the gage 29 with the straight edge 33 on the graduation 4 of scale D, and placing the gage 20 with the straight edge 24 on the 125 130

graduation of scale 12 representing the rise per foot that is being used, and placing the elbow of the square on the timber with the bearings 25 and 32 contacting with the edge 6 or side of the timber, then the outer edge of the arm or blade 10 can be used for marking the plumb cut, while the outer edge of the tongue or arm 11 is used for marking the horizontal cut. The distance between the 10 bearings 25 and 32 will represent the unit rafter length per running foot, so that by laying off consecutive distances on the timber or rafter by the aid of the bearings 25 and 32, according to the number of running 15 feet, the length of the rafter is readily obtained.

For gage positions to mark side bevels on jack rafters and face bevels on roof boards, any pitch, and polygon, the directions can 20 say "number of sides on D, rise on A". The blade 10 then marks the side bevel and the tongue 11 the face bevel. This will take care of eighty or more different pitches on each of eleven different sided (and angled) 25 buildings.

For positions of gages to mark regular hip rafters, any pitch, any polygon, the directions can say "number of sides on C, rise on blade". By marking the plumb and 30 horizontal cuts and lengths by the same method as given for common rafters, gives a large number of cuts and lengths; and by marking the depth of backing by a point along the outer edge of the tongue 11 half 35 the thickness of the rafter from the gage bearing 32, gives many more useful figures.

For miter cuts on polygons, any number of sides, directions can say "number of sides on D, 12 on blade, mark by tongue."

40 For example, to mark a regular hip side bevel on a four sided building, any pitch—set the gage 29 on 4 of scale D, and let it remain there for any pitch. Then, for a pitch of four inches "rise" set the gage 20 at 4 on scale B, and mark by the outer edge 45 of the blade or arm 10. For a "rise" of six inches set the gage 20 at 6 on scale B, etc. For jack side bevels for the same pitches, use the same figures on the scale A, with the 50 gage 29 still set at 4 on scale D.

For hundreds of irregular hip rafters, and much other difficult framing, the directions can be equally short and simple, and need not all be stated here. Some framing can be marked with the aid of only one of the scales, but in other cases it requires a combination of two scales, as in the case of jack rafter side bevels, which require the use of scales A and D.

60 Having thus described the invention, what is claimed as new is:—

1. A square, each arm of which has a straight edge and graduations for said edge thereof measured from the corresponding edge of the other arm for a unit of measure-

ment and fractions thereof, one arm having additional graduations for said edge thereof measured from the corresponding edge of the other arm and representing the lengths of hypotenuses of right triangles each having as one of its sides the unit of measurement and having as their other sides a series of increasing graduated measurements for increasing "rises" per unit. 70

2. A square, each arm of which has a straight edge and graduations for said edge thereof measured from the corresponding edge of the other arm for a unit of measurement and fractions thereof, one arm having additional graduations for said edge thereof measured from the corresponding edge of the other arm and representing the lengths of hypotenuses of right triangles each having as one of its sides the unit of measurement and having as their other sides a series of increasing graduated measurements bearing the proportion to the increasing "rises" per 80 the unit of measurement as the radius of an inscribed circle of a square bears to the radius of the circumscribed circle of such 90 square.

3. A square, each arm of which has a straight edge and graduations for said edge thereof measured from the corresponding edge of the other arm for a unit of measurement and fractions thereof, one arm having additional graduations for said edge thereof measured from the corresponding edge of the other arm and representing the lengths of the radii of the circumscribing 100 circles of a series of regular polygons.

4. A square, each arm of which has a straight edge and graduations for said edge thereof measured from the corresponding edge of the other arm for a unit of measurement and fractions thereof, one arm having additional graduations for said edge thereof measured from the corresponding edge of the other arm and representing distances proportional to the lengths of the sides of a 110 series of regular polygons. 105

5. A square, each arm of which has a straight edge and graduations for said edge thereof measured from the corresponding edge of the other arm for a unit of measurement and fractions thereof, one arm having additional graduations for said edge thereof measured from the corresponding edge of the other arm and representing the lengths of hypotenuses of right triangles each having as one of its sides the unit of measurement and having as their other side a series of increasing graduated measurements based on increasing "rises" per unit, the second named arm having additional graduations for said edge thereof measured from the corresponding edge of the first named arm and representing, in length, differences in proportions 120 of a series of regular polygons. 115

6. A square, each arm of which has a 130

straight edge and graduations for said edge thereof measured from the corresponding edge of the other arm for a unit of measurement and fractions thereof, one arm having 5 additional graduations for said edge thereof measured from the corresponding edge of the other arm and representing the lengths of hypotenuses of right triangles each having as one of its sides the unit of measurement and having as their other sides a series 10 of increasing graduated measurements for increasing "rises" per unit, the first named arm also having graduations for said edge thereof measured from the corresponding edge of the second named arm and representing the lengths of hypotenuses of right triangles having as one of its sides the unit of measurement and having as their other sides a series of increasing graduated measurements 15 bearing the proportion to said increasing "rises" per unit as the radius of an inscribed circle of a square bears to the radius of the circumscribed circle of such square, the second named arm having addi- 20

tional graduations for said edge thereof 25 measured from the corresponding edge of the first named arm and representing lengths of radii of the circumscribing circles of a series of regular polygons, the second named arm also having graduations for said edge there- 30 of measured from the corresponding edge of the first named arm and representing proportions of the lengths of the sides of such series of regular polygons.

7. A square, one arm of which has a 35 straight edge and graduations for said straight edge, and a gage slidable on said arm and having a straight edge to register with said graduations, said gage having a portion extending across and bearing against 40 said edge of the arm, said portion having an ear bent at an obtuse angle so that one corner thereof provides a knife edged bearing at the intersection of said straight edges.

In testimony whereof I hereunto affix my 45 signature.

JOHN PARKHILL.
